UNITED STATES PATENT OFFICE

156,301

DESIGN FOR A VIBRATOR UNIT

John Werner, Chicago, and Albert H. Zeigler,
Kenilworth, Ill., assignors to Aciform Corpora-
tion, Chicago, Ill., a corporation of Illinois

Application November 12, 1947, Serial No. 142,476

Term of patent 3½ years

(Cl. D83—1)

To all whom it may concern:

Be it known that we, John Werner and Albert H. Zeigler, both citizens of the United States of America and residents of Chicago and Kenilworth, in the county of Cook and State of Illinois, respectively, have invented a new, original, and ornamental Design for a Vibrator Unit, of which the following is a specification, reference being had to the accompanying drawing, forming part thereof.

Figure 1 is a perspective view of a vibrator unit showing our new design.

Fig. 2 is a top plan view thereof.

We claim:
The ornamental design for a vibrator unit, as shown.

JOHN WERNER.
ALBERT H. ZEIGLER.
